(57) **CLAIM**

The ornamental design for a thermal transfer printer, as shown and described herein.

DESCRIPTION

FIG. 1 is a front, left side, top perspective view according to my design for a thermal transfer printer.

FIG. 2 is a front view of the thermal transfer printer shown in FIG. 1.

FIG. 3 is a rear view of the thermal transfer printer shown in FIG. 1.

FIG. 4 is a right side view of the thermal transfer printer shown in FIG. 1.

FIG. 5 is a left side view of the thermal transfer printer shown in FIG. 1.

FIG. 6 is a top view of the thermal transfer printer shown in FIG. 1; and,

FIG. 7 is a bottom view of the thermal transfer printer shown in FIG. 1.

The broken lines represent unclaimed portions of the article, and form no part of the claimed design.

1 Claim, 7 Drawing Sheets
